TELEVISION SYSTEM

Eric Lawrence Casling White, Hillingdon, Middlesex, England, assignor to Electric & Musical Industries Limited, Hayes, Middlesex, England, a company of Great Britain

Application October 5, 1938, Serial No. 233,342
In Great Britain October 15, 1937

4 Claims. (Cl. 178—69.5)

This invention relates to television systems and is particularly concerned with circuits for obtaining synchronism between the operation of scanning at a receiver with that at a transmitter.

5 In certain television systems known at the present time synchronizing is effected by utilizing synchronizing pulses which are transmitted in the blacker than black sense, these pulses being superposed upon the picture signals so that they
10 can be separated from the picture signals by a device which discriminates between the amplitude of pulses applied to it. In such systems, it is usual to make the frame synchronizing pulses of greater duration than the line frequency synchronizing pulses, and various proposals have been made for effecting discrimination between
15 these two types of pulses.

In a television system employing interlaced scanning in which the odd numbered lines in one frame are interlaced with the even numbered lines in another frame, it is necessary that the discriminating device should not be affected by the position of the line synchronizing pulse immediately preceding the frame synchronizing
25 pulse because the position of that pulse varies in alternate frames by a half a line period.

By the disclosure of British Patent No. 455,375, the problems involved in obtaining synchronism are discussed, and alternative synchronizing
30 pulse separating circuits are described, such circuits being for use in television systems employing frame pulses of relatively long duration and line pulses of relatively short duration, but of the same amplitude, both line and frame pulses being transmitted in the blacker than black sense. In certain arrangements described in the named British patent, a condenser is charged through a resistance and shunted by a tube which is positively biased, and is, therefore, conducting in
35 the intervals between pulses. The condenser charges during pulses and a sawtooth voltage waveform is produced, the pulses of which are of duration equal to that of the pulses producing them but of greater amplitude in the case of the longer frame pulses. By applying both derived
40 sawtooth pulses to an amplitude selecting device the pulses of larger amplitude operate to produce pulses which are applied to the frame deflecting apparatus.

45 In one arrangement described in the patent referred to, an inductance is inserted in series with a resistance in the anode lead of a tube and the time constant of the coil and resistance are made longer than the duration of a frame pulse.
50 The synchronizing pulses are applied to the grid

of the tube which is so negatively biased as to be conducting only when the synchronizing pulses are applied in the positive sense between the grid and cathode of the tube.

The object of the present invention is to provide
5 an improved frame and line pulse separating circuit in which irregular operation of the circuit due to interference or to the effect of adjacent pulses upon each other is avoided or reduced.

According to the present invention a circuit
10 arrangement for developing signals which are used to effect selection from a mixture of pulses such as synchronizing pulses which are of differing duration, those pulses which exceed a certain duration, includes a switching device such as a thermionic valve which is conductive and applies a substantially constant potential to an inductance for the duration of each synchronizing pulse and is rendered non-conductive at the end of the pulse, the energy stored in the inductance being diverted into a capacity which may be constituted by the stray capacity of the inductance or by a condenser provided for the purpose, said capacity being effectively in shunt with the inductance so that the potential reached
15 by the capacity is proportional to the duration of the pulse. The developed signals may be utilized in any desired manner to effect selection of the pulses of longer duration and known forms of amplitude selecting devices may be used
20 for this purpose. In a particular application of the present invention the potential resulting from the charging of said capacity is applied to the grid of a discharge device constituting an element in a circuit for generating a sawtooth waveform for deflecting purposes. The inductance and capacity may be shunted by a resistance in
25 order to prevent the oscillatory condition set up by each pulse from persisting.

In order that the invention may be more clearly understood and readily carried into effect, alternative forms of circuit arrangement embodying the invention will now be described more fully by way of example with reference to the accompanying drawings wherein:

Fig. 1 shows one such form of circuit;

Fig. 2 is an explanatory diagram illustrating waveforms of grid voltage and anode current;

Fig. 3 illustrates a possible modification of Fig.

1; and

Fig. 4 shows a still further modification where-in the so-called blocking oscillator tubes are used in the scanning system.

Referring to the drawings, the synchronizing signals are applied from a suitable input circuit

- in the positive direction to the control electrode or grid of a tube 1 through a condenser 2, a grid leak resistance 3 being provided so that D. C. establishment occurs at the grid of the tube 1.
5. The synchronizing signals are of sufficient amplitude to cause anode current in the tube 1 to be cut-off in the intervals between the pulses, the potential waveform applied to the grid being as shown at 4 in Fig. 2a of the drawings. It will 10 be seen that operation in this manner permits picture signals also to be present at the input of the tube 1. This tube is preferably of the pentode type or it may be a tetrode having a characteristic curve without the usual kink. The 15 tube employed is operated at the portion of its characteristic curve at which the tube impedance is low.

When the tube 1 is rendered conductive by a synchronizing pulse, the anode potential drops to 20 a low value as indicated in the curve 5 of Fig. 2b and current starts to increase in an inductance 6 in the anode lead of the tube 1. At anode current cut-off which occurs at the end of the pulse the current in the coil is diverted into the capacity 7, represented by a condenser in the drawings but which may be constituted by stray capacities, the capacity being charged in a sense opposing the charging current so that the voltage at the anode of the tube 1 increases positively. The capacity is charged in a quarter of a free oscillation period of the natural frequency of the inductance 6 and capacity 7 which should be about 10 micro-seconds or less in the case of 30 high definition television systems employing line frequencies of the order of 10,000 per second or higher.

The amount to which the anode potential of the tube 1 rises is substantially proportional to the duration of the pulse as illustrated in Fig. 2b. Thus, it may be arranged that the oscillation following a frame pulse is of sufficient amplitude to trigger a hot cathode grid controlled discharge tube (such, for example, as a tube of the type known as "thyatron" or "885" type) but that the oscillation following a line pulse is of insufficient amplitude to do so. As shown in the drawings, the grid of a grid controlled tube 8 is connected or coupled to the anode of tube 1, through a condenser 9.

40. A resistance 10 is connected across the circuit including inductance 6 and capacity 7, the value of the resistance being chosen to give critical damping or almost critical damping. The purpose of the resistance is mainly to insure that the oscillation set up by each synchronizing pulse 45 may have substantially ceased before the next pulse arrives. The circuit arrangement shown will operate with any system in which the frame synchronizing pulses are of greater time duration than the line synchronizing pulses.

60. The modification of the circuit of Fig. 1 which has been shown in Fig. 3 consists in the provision of an extension 11 of the inductance coil 6, the effective coupling of the portion 11 to 6 enabling the positive line frequency pulses to be passed to a line scanning device connected to the terminal 12. The frame scanning device is connected to the terminal 13, or preferably to a tap 14 in order to low the effective impedance of the coil 6. This facilitates the connection of the inductance to other apparatus.

When the scanning devices are of the blocking oscillator type, as shown more particularly by

Fig. 4, the pulses from the tapping points 12 and 14 may be fed to the oscillators 16 and 21 through condensers 15 and 20 in the manner shown. Referring to this drawing, it will be seen that the circuit arrangement of the tube 1 is similar to 5 that shown in Fig. 3 and the connection from the end of the inductance 6 is taken through a condenser 15 to the control grid of a blocking oscillator tube 16, the screening grid of which is shown coupled by a transformer 17 to the control 10 grid. The value of the condenser 15 is chosen small compared with the value of the blocking oscillator grid condenser 18. The blocking oscillator valve operates in the manner set forth and described by Tolson and Duncan in their U. S. 15 Patent #2,101,520 granted December 7, 1937 (see also British Patent #402,629). A sawtooth potential at the line frequency is taken from the terminal 19.

A connection is taken from the tapping point 20 14 through a condenser 20 to the control grid of a further blocking oscillator tube 21, the connections of which are similar to those of the tube 16. Again, in this case the value of the condenser 20 is chosen smaller than the blocking 25 oscillator grid condenser 22. Sawtooth potentials at the frame frequency can be taken from the terminal 23. By suitable choice of the values of the coupling condenser 15 and 20, the strength of the synchronization can be adjusted to give 30 least trouble from interference.

Having now described the invention, what is claimed is the following:

1. An apparatus for segregating pulses having substantially the same amplitude and of differing duration comprising a thermionic valve having anode, cathode and at least one control electrode, means for rendering said valve normally non-conducting, an inductive member connected in the anode-cathode circuit of said valve, means for impressing said impulses of differing duration onto a control electrode of said valve whereby the valve is rendered conducting during receipt of said impulses, a capacity connected substantially in parallel with at least a portion of said inductance, and a load circuit connected 40 to the inductance and condenser parallel combination.

2. Apparatus in accordance with claim 1 wherein there is provided in addition a damping resistance connected substantially in parallel 50 with said condenser.

3. Apparatus for separating signals having substantially the same amplitude and differing durations comprising a thermionic vacuum tube having anode, cathode and at least one control electrode, means for rendering said tube normally non-conducting, a tapped inductive member connected in the anode-cathode circuit of said tube, a condenser connected substantially 55 in parallel with a tapped portion of said inductive member, a pair of load circuits, means for connecting said load circuits to differing sections of said inductive member, and means for impressing said signals of differing duration 60 onto a control electrode of said tube whereby said tube is rendered conducting during the receipt of said signals.

4. Apparatus in accordance with claim 3 wherein there is provided in addition a resistance connected substantially in parallel with said 65 condenser.
